**FLEXIBLE CHAIN EXTENSION OR SHANK FOR
TOOLS WITH LOCK LINK FEATURES****Robert B. Jones, 829 Kenmore Blvd., Akron, Ohio****Filed Jan. 21, 1964, Ser. No. 339,193****2 Claims. (Cl. 81—177)**

This invention relates to a flexible chain extension or shank for tools, which links of the chain extension can be locked in fixed relationship to set the position of the chain after it has been flexibly bent to the desired shape in order to provide extensions for socket wrench sets and the like to facilitate the application of the tools to, and the use of tools in hard-to-get places.

This invention is an improvement of my previous patent entitled "Flexible Extension or Shank for Tools," Patent No. 3,002,409. This patent helps eliminate the typical problem, for example in U.S. Patent No. 1,316,398, and my previous patent where the links of the chain are so free and floppy in the plane in which they have bending movement that control of the tool is difficult and annoying. It is highly desirable to provide a flexible extension which can then be made rigid and fixed for application to nuts and bolts in locations where known tool equipment cannot function efficiently, or at all.

Therefore, it is the general object of the present invention to avoid and overcome the foregoing and difficulties of and objections to prior art practices of the type described by the provision of relatively simple, inexpensive and practically flexible extensions or shanks for tools of the type described which can be made fixed and rigid after being adapted to the proper position, and which extensions will facilitate and aid a mechanic and a machinist in performing machine work otherwise impossible, particularly annoying, or difficult to perform because of the inaccessibility of the work.

Another object of the invention is to provide a flexible extension or shank for a tool made from a flexible chain link whereby the links can be selectively locked in fixed relationship to each other by means of small wrenches carried in a shank member affixed to one end of the linked chain.

Another object of the invention is to provide a chain link extension for a socket type tool whereby longitudinally split sleeves hold the chain links together and tapered bolt means are adapted to spread the split sleeves so the sleeves engage the links and selectively lock them into fixed relationship with each other after the chain link extension has been adjusted to the proper position.

The aforesaid objects of the invention, and other objects which will become apparent as the description proceeds are achieved by providing in a tool the combination of a plurality of chain links, a plurality of hollow longitudinally split sleeve means pivotally connecting the chain links together to provide a linked chain freely bendable in one plane but not bendable in any other, an internally threaded spacer means slidably received inside each split sleeve means, tapered bolt means operatively screwed into said internally threaded spacer means and adapted to engage the inner surface of said split sleeve means to be selectively locked in fixed relationship, a socket secured at one end of the chain and adapted to removably receive in plug-in fashion the polygonal post of a handle, and a polygonal post secured to the other end of the chain and

2

adapted to removably receive in plug-on fashion the socket of a tool.

For a better understanding of the invention reference should be had to the accompanying drawings, wherein:

5 FIGURE 1 is a side elevation, partially broken away, of a flexible extension incorporating the principles of the invention;

10 FIGURE 2 is a fragmentary view of an embodiment of the invention in which a handle is permanently secured to a flexible shank;

FIGURE 3 is a fragmentary side elevation of a straight handle adapted to be removably secured in the socket end of the extension of FIGURE 1;

15 FIGURE 4 is a fragmentary side elevation of a ratchet handle adapted to be secured in the socket portion of FIGURE 1;

FIGURE 5 is a fragmentary side elevation of a rotary type handle adapted to be removably secured in the socket portion of FIGURE 1;

20 FIGURE 6 is a side elevation of a socket adapted to be removably secured in the plug end of the extension of FIGURE 1;

FIGURE 7 is a perspective view of an open-ended wrench having a socket portion adapted to be removably secured in the plug of the extension of FIGURE 1;

FIGURE 8 is a perspective view of a closed-end wrench having a socket portion adapted to be removably secured in the plug of the extension of FIGURE 1;

FIGURE 9 is a horizontal cross sectional view of the 30 link locking features of the invention taken on line 9—9 of FIGURE 1;

FIGURE 10 is a plan view of the split sleeve and tapered locking nuts utilized to achieve the locking features of the invention.

35 FIGURE 11 is a fragmentary plan view of a polygonal plug attachment operatively affixed by locking means to the end of the chain which plug carries locking wrenches in its body portion;

FIGURE 12 is a fragmentary elevation of the polygonal 40 plug of FIGURE 11; and

FIGURE 13 is a fragmentary cross sectional view of a nut in a hard-to-reach position showing how the extension of the invention is easily formed to reach the nut and that it can be locked in this position.

45 With specific reference to the drawings, in FIGURE 1, the numeral 10 indicates generally a pivoted link chain freely bendable in one plane and having little or no bending movement in any other plane. Secured to one end of the chain is a socket member 12 adapted to removably 50 receive in a socket recess 14 a polygonal plug of any one of a plurality of handles, for example, such as shown in FIGURES 3, 4, and 5.

The handle of FIGURE 3 includes a polygonal plug 16 and a spring detent 18 adapted to be removably received 55 in the socket opening 14 of the socket 12.

FIGURE 4 shows a ratchet type handle with a ratchet mechanism 20, handle 22, and a polygonal plug 24 which includes a spring detent 26 adapted to be removably received in the socket opening 14 of the socket 12.

60 The handle of FIGURE 5 includes a handle portion 28 rotatably receiving a rotary brace 30 which terminates in a polygonal plug 32 having a spring detent 34, and with the plug 32 removably fitting in the socket opening 14 of the socket 12.

The other end of the chain 10 has secured thereto a polygonal plug 36 having a spring detent 38, the plug 36 being adapted to removably fit in any of a plurality of tools, for example, those shown in FIGURES 6 to 8.

In FIGURE 6 is shown a socket 40 having an opening 42 adapted to fit a certain size nut or bolt head, the other end of the socket having an opening 44 adapted to removably receive the polygonal 36.

FIGURE 7 shows an open end wrench 46 having a socket opening 48 adapted to removably receive the polygonal plug 36. The socket opening 48 is adapted to receive the plug 36 and the spring detent 38 in such relation that the flat plane of the wrench 46 is parallel to the pivots in the chain 10, so torque can be applied through the chain to rotate the opened end wrench 46 in its own plane.

In FIGURE 8 is illustrated a closed end wrench 50 having a socket opening 52 adapted to removably receive the polygonal plug 36, again insuring that the flat plane of the wrench is parallel to the pivots in the chain so that torque can be applied through the chain to rotate the flat wrench in its own plane.

However, although it is desirable to mount the wrenches 46 or 50 or the socket 40 to insure that they are parallel to the pivots in the chain so that torque is applied through the chain, it is not absolutely necessary, as the essential and important feature of the invention is that the individual links of the chain can be locked in fixed relationship to each other. In order to understand this relationship, reference should be had to FIGURE 9, wherein it is shown that the locking mechanism comprises an outer sleeve 60 extending through aligned holes in a plurality of stacked chain links 62. A shorter internally threaded spacer member 64 is slidably received inside the outer sleeve 60. A pair of tapered socket head set screws 66 and 68, respectively, are threadably received in the internal threads of the spacer member 64. Tapered portions 70 and 72, respectively, of the set screws 66 and 68 engage the internal surfaces of the outer sleeve 60 exerting outward pressure thereon as they are screwed down into the spacer member 64. With reference to FIGURE 10, it is seen that the outer sleeve 60 contains a longitudinal slit 74 extending the length thereof. Therefore, as the tapered surfaces 70 and 72 of the set screws 66 and 68 are screwed tightly into the spacer member 64, the outer sleeve 1 is spread apart along slit 74 to effect a binding, locking action as the sleeve 60 engages against the surfaces of the holes in the links 62. A similar set screw locking sleeve arrangement is incorporated to join all of the links of the chain as well as to join the socket member 12 and the polygonal plug 36.

Also, as an important feature of the invention, it is contemplated that the spacer member 64 will be considerably shorter in length than the sleeve 60 so that the tapered portions 70 and 72 of the set screws 66 and 68 can adequately engage the inner portion of the sleeve 60 to effect the spreading action described above. Also, it is contemplated that the tapered relation of the surfaces 70 and 72, as indicated by the angle 80 on surface 72, will be between about 15 to about 20 degrees to effect the spreading locking action on the sleeve 60 as the set screws are screwed into the spacer member 64. It is contemplated that both set screws 66 and 68 will be screwed into the opposed internally threaded portions of the spacer member together to effect an equal spreading action to the outer sleeve 60 so that all the links 62 specifically joined by the sleeve 60 will be locked in a fixed relation to each other. The spacer sleeve 60 will generally be made from a known spring type hard steel while the set screws 66 and 68 and the spacer member 64 will be generally machined from steel. The internal ends of the sleeve 60 may be internally tapered to receive the tapered surfaces 70 and 72 of the set screws 66 and 68, so that a smooth spreading action will be obtained when the set screws 66 and 68 are tightened.

Thus, it is seen that any and all of the links in the chain

can be selectively locked in fixed relation to each other simply by tightening the set screws to spread the sleeves holding the links together. As a convenient means to have wrenches available to effect the locking of the set screws, the invention contemplates that a polygonal shank 82 as shown in FIGURE 11, is operatively affixed to links 62a by means of a sleeve set screw arrangement, indicated generally by numeral 60a.

The shank 82 contains a polygonal plug 84 having a detent 86 thereon. The shank 82 also contains a pair of elongated slots 88 and 90 adapted to receive a pair of Allen set screw wrenches 92 and 94, respectively. A removable collar 96 is operatively positioned over the ends of the wrenches 92 and 94 and held in position on the shank by a spring loaded detent 98. Thus, the set screw wrench 92 and 94 are operatively positioned in the shank 82 for ready access to lock or unlock the link portions of the extension of the invention, as described above with reference to FIGURES 9 and 10.

FIGURE 13 illustrates the chain 10 bent and locked into position so that a socket 100 is adapted to be positioned over a nearly inaccessible nut 102. Note the relationship of an extended shank portion 82a in this situation with a knurled handle 82b attached thereto. It is contemplated that in the unlocked relation the link chain 10 will be stiff enough so that after it has been flexibly adjusted to position, it can be removed without losing the desired adjustment and then locked in position so that when force is applied to remove the nut 102, the tool will act as a solid member. Also, it should be noted that with the link chain 10 locked into fixed relationship, torque may be applied both in the plane of the links and normal to the plane of the links. However, it is generally best to force the plane of the links to prevent undue stress on the locked links.

Thus, it is seen that an improved link chain extension which can be locked into position for access to nearly inaccessible nuts and bolts has been provided. The locking is achieved by spreading a longitudinally split sleeve by means of tapered set screws engaging a spacer member and being screwed thereinto to effect the spreading of the spacer sleeve. The locking wrenches can be carried in a shank portion adjacent the handle of the link chain extension.

While in accordance with the patent statutes, only one best known embodiment of the invention has been illustrated and described in detail, it is to be particularly understood that the invention is not limited thereto or thereby, but that the inventive scope is defined in the appended claims.

What is claimed is:

1. An extension for a set of socket wrenches or the like including a pivoted link chain comprising a plurality of links freely bendable in one plane, but not bendable in any other,

55 a socket secured at one end of the chain and adapted to removably receive in plug-in fashion the polygonal post of a handle,

a polygonal post secured to the other end of the chain and adapted to removably receive in plug-on fashion the socket of a tool,

60 a plurality of sleeves split their full longitudinal length along a single line connecting the links of the chain together and connecting the socket and the polygonal post to their respective ends of the chain, an internally threaded spacer member slidably received inside each sleeve, and

65 tapered bolt means removably screwed into each end of said spacer members and engaging the inner surface of said sleeves effecting spreading thereof equally along the full length of the single line split to selectively lock the links, socket, and polygonal post into fixed relationship to each other.

2. In an extension for a set of socket wrenches or the like the combination of

a pivoted link chain comprising a plurality of links freely bendable in one plane, but not bendable in any other,
 a socket secured at one end of the chain and adapted to movably receive in plug-in fashion the polygonal post 5
 of a handle,
 a polygonal post secured to the other end of the chain and adapted to removably receive in plug-on fashion the socket of a tool,
 a plurality of sleeves split their full longitudinal length 10 along a single line connecting the links of the chain together and connecting the socket and the polygonal post to the respective ends of the chain, and
 tapered lock bolt means removably screwed into each end of said sleeves and engaging the inner surface of 15 said sleeves to effect equal spreading thereof at the split along their full length whereby said chain links

are uniformly engaged by said split sleeves to selectively lock the links, socket, and polygonal post into fixed relationship to each other.
